UNITED STATES PATENT OFFICE

HARRY W. LAWRENCE, OF DENVER, COLORADO, ASSIGNOR, BY DIRECT AND MESNE ASSIGNMENTS, TO JEWELITE INC., A CORPORATION OF COLORADO

ELECTRIC SIGN

Application filed November 22, 1930. Serial No. 497,525.

This invention relates to an electric sign and has for its principal object the provision of a sign which will produce a brilliant, glistening effect both by day and night. This principal object is accomplished by means of a series of small cut or molded lenses or jewels, preferably of the type having a multitude of angularly positioned facets.

It has been found that satisfactory results can not be obtained from such lenses or jewels if they are illuminated by means of direct light rays from behind. Direct light rays produce a spotty effect, that is, some of the jewels will be illuminated and perhaps parts of others, the remainder being totally without illumination. This apparently is caused by the fact that the direct light rays are refracted at a certain angle by each facet. Therefore, only certain of these rays will strike the eye so that the remainder of the facets and jewels will remain dark.

Another object of this invention is to avoid the above uneven illumination and illuminate all of the facets of all of the jewels so as to form a uniformly brilliant effect. It has been found that this can be accomplished by preventing direct rays from the light source or sources from striking the jewels and by illuminating them totally by diffused reflected light. In this way the light strikes the jewels at an infinite number of angles so that each facet will refract the light in an infinite number of angles. Therefore, no matter from which angle the sign is viewed one or more of the rays from each facet will strike the eye and all of the facets of all of the jewels will appear brilliantly illuminated.

Other objects and advantages reside in the detail construction of the invention, which is designed for simplicity, economy, and efficiency. These will become more apparent from the following description.

In the following detailed description of the invention reference is had to the accompanying drawings which forms a part hereof. Like numerals refer to like parts in all views of the drawings and throughout the drawings.

In the drawings:

Fig. 1 is a perspective view of the invention constructed to display in outline a single letter. It is, of course, to be understood that the sign could be made in any size or shape to carry out complete words, characters, displays, etc.

Fig. 2 is a horizontal section, taken on the line 2—2, Fig. 1.

Fig. 3 is a detail perspective view looking at the inside of the sign face.

The invention comprises a sign face 10 adapted to carry any desired display, or character, such as illustrated at 11. The character 11 is illuminated by means of a series of small jewel-like lenses 12. Another way to form the sign face would be to have the entire face covered with lenses and have the characters themselves without lenses or with lenses of a different color. The sign face 10 is covered at its back by means of a suitable sign box 13 which should be impervious to the passage of light. The inside of the sign box should be covered with white or aluminum paint or be provided with some similar light reflecting and diffusing material.

The electric lamps which illuminate the lenses 12 are indicated at 14. It will be noted that these lamps are carried upon the sign face 10 so as to be positioned alongside of the lenses 12. The lamps 14 may be supported in any desired manner. As illustrated they are supported in a continuous, current-carrying molding 15, such as illustrated more in detail in applicant's co-pending application, Serial No. 497,524.

By positioning the lamps 14 upon the sign face 10, it is practically impossible for any of the direct light rays to be projected outwardly through the lenses 12. To further prevent the direct rays from striking the lenses, shields 16 may be provided between the lamps 14 and the lenses to prohibit any direct rays from striking the lenses.

It will be noted that the only light reaching the inside face of the lenses 12 is that reflected from the interior surfaces of the box 13, and the shields 16. This reflected light, of course, is so diffused that it comes from an infinite

number of points on these surfaces and enters the lenses at an infinite number of angles so that no matter at what angle the lenses 12 are viewed, light rays will strike the eye from all of the facets from each of the lenses creating a uniformly brilliant effect throughout the entire series of lenses.

While a specific form of the improvement has been described and illustrated herein, it 10 is desired to be understood that the same may be varied, within the scope of the appended claims, without departing from the spirit of the invention.

Having thus described the invention, what 15 is claimed and desired secured by Letters Patent is:—

1. An electric sign comprising: a sign face perforated to outline a sign character; a sign box closing the rear of said sign face; electric 20 lamps carried by said sign face; faceted lenses carried in the perforations in said sign face; and shields projecting inwardly from said sign face so as to shield said lamps and prevent the direct rays thereof from passing 25 through said lenses, said shields forming an inwardly projecting outline for said sign character.

2. An electric sign comprising: a sign box; a sign face outlining a sign character in said 30 sign box; a series of lenses carried by said sign face; means for illuminating said lenses from the interior of the box; and shields for preventing the direct rays of light from said illuminating means for impinging upon said 35 lenses, said lamps forming a border upon the interior of the sign face about said sign character.

3. In an electric sign having a series of 40 jewels outlining a sign character in a sign face, an inwardly projecting shield on the rear of said sign face having an outline corresponding to said sign character and bordering the latter; and a series of lamp globes carried upon the rear of said sign face about 45 said shield.

In testimony whereof, I affix my signature.

HARRY W. LAWRENCE.
